UNITED STATES PATENT OFFICE

2,127,707

MACHINE FOR OPERATING ON SHOES

Laurence E. Topham, Wenham, and Clyde L. Knott, Beverly, Mass., assignors to United Shoe Machinery Corporation, Paterson, N. J., a corporation of New Jersey

Application March 6, 1937, Serial No. 129,458

21 Claims. (Cl. 12—17)

The present invention relates to machines which are used in the manufacture of shoes to perform certain operations progressively along the bottom margin of a shoe, and is herein disclosed as embodied in an automatic edge trimming machine having a shoe supporting jack and actuating mechanism for imparting tipping, turning and feeding movements to the jack to transfer the point of operation about the shoe, together with a templet which is supported in a fixed predetermined relation to the shoe, and serves to determine the contour outline followed by the trimming cutter around the sole.

Experience has shown particularly in the performance of rough rounding and edge trimming operations, that a templet supported in a fixed predetermined relation to the shoe, and operating against a relatively stationary guide, provides an extremely accurate and efficient means for producing a contour of the shoe sole corresponding to the shape of the templet. In order to adapt this principle of a templet guiding means for commercial use, various attempts have heretofore been made with a single templet to cause the shoe operating devices to follow any one of a plurality of predetermined contour paths about the sole margin of a shoe supported in predetermined relation to the templet and thereby to reduce so far as possible the number of templets which must be furnished to adapt the machine for commercial use over a wide range of sizes and shapes of shoes. To this end, width grading devices having been employed as described and illustrated in the patent to Alfred R. Morrill No. 2,050,499, dated August 11, 1936, which operate during the transfer of the operation about the shoe to control the forward and back position of the relatively stationary templet guide with relation to a master templet shaped for a definite length of shoe, to cause the trimming cutter to follow any one of a plurality of predetermined contour paths corresponding to different widths of shoe. Such a device, however, is of only limited application in view of the fact that separate templets must necessarily be supplied for each length and style of shoe.

It is a principal object of the present invention to provide guiding means cooperating with a single master templet to locate the shoe laterally with relation to the shoe operating means at the point of contact which is adjustable to cause the operating means to follow any one of a plurality of predetermined contour paths about the shoe determined in accordance with the length of shoe being operated upon.

It is a further object of the invention to provide means to control the relative positions of a templet edge gauge and a master templet of this general description during the transfer of the operation about the margin of the shoe sole which is adjustable to cause the shoe operating devices to follow any one of a number of predetermined contour paths which are determined in accordance with both the length and width of shoe being operated upon.

With these and other objects in view, as may hereinafter appear, the several features of the present invention consist in the devices, combinations and arrangement of parts hereinafter described and claimed which, together with the advantages to be obtained thereby, will be readily understood by one skilled in the art from the following description taken in connection with the accompanying drawings, in which Fig. 1 is a view in front elevation of an automatic edge trimming machine embodying the several features of the present invention; Fig. 2 is a plan view of the machine illustrated in Fig. 1, but with the stop motion removed; Fig. 3 is a somewhat simplified plan view similar to Fig. 2, but with the length sizing device set for operation upon a larger size shoe; Fig. 4 is an enlarged detail view illustrating particularly the mechanism for clamping the heel of a shoe supported on the jack laterally with relation to the templet; Fig. 5 is an enlarged view taken on the line 5—5 of Fig. 2, illustrating particularly the supporting and actuating mechanism for the templet guide; Fig. 6 is an enlarged detail view of the sun and planet gear control mechanism forming part of the length size grading device to determine the in-or-out position of the templet guide roller; Fig. 7 is a view in right side elevation of the mechanism shown in Fig. 6, with a portion of the casing broken away to show underlying parts; Fig. 8 is an enlarged detail view of the manually operable length size adjustment mechanism in the position shown in Fig. 2; Fig. 9 is a detail view partly in section taken on the line 9—9 of Fig. 8; Fig. 10 is a detail sectional view taken on the line 10—10 of Fig. 2; Fig. 11 is a detail sectional view taken on the line 11—11 of Fig. 2; Fig. 12 is an enlarged detail view of certain adjusting connections shown generally in Figs. 2 and 3; Fig. 13 is a sectional view taken on the line 13—13 of Fig. 12; Fig. 14 is an enlarged detail view of the manual control for the width grading mechanism; Fig. 15 is a sectional view taken on the line 15—15 of Fig. 14; Figs. 16, 17 and 18 are somewhat diagrammatic plan views

showing three different lengths of shoe assembled with the templet and the positions of the templet guide roller and the edge trimming cutter with relation thereto, Fig. 16 showing the operation on a size 5C shoe, Fig. 17 showing the position of the parts for operating upon an 8C shoe, and Fig. 18 showing the position of the parts for operating upon an 11C shoe; and Fig. 19 is an explanatory diagram in which the direction and proportional amount of the corrections made in the position of the templet roller with relation to the trimming cutter for different lengths of shoe of the same width size have been plotted for a large number of positions in the transfer 15 of the point of operation around the shoe.

The automatic edge trimming machine disclosed in the drawings as embodying in a preferred form the several features of the present invention, comprises a base 20 on which is supported an edge trimmer head 22, a housing 24 for the stop motion of the machine, together with a shoe supporting jack 26 and the various supporting and controlling mechanisms therefor. The edge trimming devices, as best shown in Figs. 1 and 5, consist in an edge trimming cutter 28 of ordinary description which is supported on a downward extension of the armature shaft 30 of an electric motor 32 rigidly supported on the head 22.

The shoe supporting jack 26 comprises the toe supporting arm 27 which forms an upward extension of a jack spindle 29, and has mounted thereon the toe rest 31 and the pivoted heel supporting arm 33 and heel post 34. The jack, as thus far described, is substantially similar to jacks of this general description well known in the art, and is arranged for operation in the usual manner, in which the positioning of a shoe and associated last on the heel post with the jack in open position operates to close and lock the jack with the toe in gripping engagement with the toe rest 31. The construction and mode of operation of the jack is substantially similar to that disclosed in the patent to Morrill No. 1,689,594, dated October 30, 1924.

The jack disclosed in the drawings is also provided with a templet guide 36 which is rigidly secured to the toe rest 31, and extends around the shank and forepart portions of the shoe. It will readily be seen that the templet supported in this manner will occupy identically the same position with relation to the toe portion of any shoe which is mounted in the jack regardless of variations in length or width. In order to insure the correct positioning of the heel portion of a shoe laterally with relation to the jack, and more particularly with relation to the templet guide 36, a heel clamp is provided comprising two gripper levers 38 and 40 which are mounted on a laterally extending bracket 42 formed as a unit with the heel post 34 which fits loosely into a corresponding socket formed in the last, and are arranged for gripping engagement with portions of the shoe upper on opposite sides of the heel. The operation of the heel grippers 38 and 40, as best shown in Fig. 4, is controlled by means of a hand lever 44 pivotally mounted at 46 on the heel supporting arm 33 and provided with a V-shaped extension 48 which engages with a pivot pin 50 for two toggle links 52 and 54 connected at their outer ends respectively to the gripper levers 38 and 40. A tension spring 56 connected between the lower ends of the gripper levers 38 and 40 tends normally to maintain the levers in open position. An upward movement

of the hand lever 44 operates to straighten the toggle connection 52, 54 against the pressure of the tension spring 56, and move the gripper levers 38 and 40 into gripping engagement with the heel portion of a shoe supported on the jack. 5 This gripping engagement is maintained by means of a ratchet locking device including a spring-pressed plunger 55 supported in the handle of the lever 44 and arranged for engagement with the teeth of a rack on the heel supporting 10 arm 33. It will readily be seen that the heel gripping devices constructed and arranged as above set forth, will operate to position the heel portion of the shoe laterally to bring the center line of the heel into the same position irrespective 15 of variations in size or width, so that the shoe will always be supported in an exactly predetermined relationship to the templet guide 36.

The mechanism herein disclosed for supporting and moving the jack to transfer the point of 20 operation about the shoe, is substantially similar to mechanisms of this general type well known in the art, but may be briefly described as follows:—The jack supporting structure comprises an arm 57 in the forward end of which the lower 25 end of the jack spindle 29 is rotatably mounted by means of a gimbal joint, and a support 53 on which the arm 57 is mounted to swing vertically in a frame 51 pivotally mounted at its lower end in the machine base so as to be capable of swing- 30 ing about a horizontal axis, and upon which the support 53 is mounted to swing about a substantially vertical axis. The mechanism for moving the jack in the direction of feed, for rotating the jack, and for imparting tipping movements to 35 the jack, comprises a vertical cam shaft 58 upon which a series of pattern cams 59 are mounted, and connections from the cam shaft to the jack and jack supporting structure comprising the feed lever 60 connected by the link 61 to the toe 40 portion 31 of the jack, the cord 62 passing around a wheel 63 mounted in the forward end of the arm 57 and connected through the gimbal joint to the jack spindle 29, and cam levers 64 and 65 connected respectively to the frame 51 and sup- 45 port 53.

In accordance with the usual construction of the jack actuating mechanism for automatic machines of this general description, a number of banks of cams for performing each of the feeding, 50 turning and tipping operations are mounted on the cam shaft 58 and may be rendered operative alternatively to control the operation of the jack by a vertical adjustment of the cam shaft 58 and cams 59 supported thereon.

The operation of the jack actuating mechanism to impart the correct turning and tipping movements to the shoe during the transfer of the point of operation about the shoe sole is automatically adjusted in accordance with the length size of 60 shoe being operated upon by means of connections controlled by the feed lever 60 as the shoe supported on the jack is brought to its starting position in the machine. These connections are fully set forth in the patent to Topham and 65 Morrill No. 1,616,714, issued February 8, 1927, but may be briefly described in connection with Fig. 2 of the drawings as follows:—The feed lever is connected by means of links 66 and 67 to one arm of a lever 68, the other arm of which engages a cam 70 on the pattern cam shaft. The links 66 and 67 are pivotally connected together and to the free end of a swinging guiding link 69. The link 69 is fulcrumed upon a lever 70 which is held locked in position during the operation on a shoe. To 75

adapt the machine for operation on shoes of different sizes, the lever 70 is pivotally mounted upon the machine base so that it can be adjusted to change the position of the fulcrum of the swinging guiding link 69. The fulcrum carrying lever 70 is held locked in adjusted position during the operation on the shoe by mechanism comprising a rod 71 pivotally connected to the rear end of the fulcrum carrying lever 70 and arranged to slide in a block pivotally mounted on the machine base. The rod 71 is engaged by the inner cam shaped ends of short levers 72 mounted in the block and the outer ends of these levers are connected by a pin and slot construction with a cross bar 73. This cross bar is pivotally mounted on the rear end of a rod 74, the forward end of which is pivotally connected to a bar 75. The bar 75 at one end is connected to one arm of a lever 76 and near its other end is connected by a link 77 to one arm of a lever 78, the hub of which is arranged to be engaged by a latch 79. During the operation on a shoe, the lever 78 is held by the latch 79 and the fulcrum carrying lever 70 is locked in position. The placing of a new shoe on the jack acts to release the lever 78, so that the fulcrum carrying lever 70 is unlocked, and adjustment of the mechanism for actuating the feed lever can be made by the movement of the jacked shoe to starting position in the machine. The fulcrum carrying lever 70 is locked in position on starting the machine by means of a pin 80 on a horizontally arranged bar 81, which pin as the bar is moved to the right, swings the lever 78 until it is engaged by the latch 79. The bar 81 is a part of the starting mechanism and is connected by means of a bell crank lever and connecting rod to the starting treadle of the machine.

At this point, it may be noted that the bar 75 of the mechanism for locking and unlocking the fulcrum carrying lever of the feed mechanism is also utilized to adjust the speed of the pattern cam shaft in accordance with the size of the shoe to be operated on, the arm 76, to which one end of the bar 75 is connected, acting when moved in either direction to adjust the variable speed mechanism through which the pattern cam shaft is driven. The arm 76 is moved into the proper position by a longitudinal movement of the controller bar 75 imparted thereto by the engagement of a pin 82 on a forward extension of the lever 78 with one of two inclined surfaces formed on the end of the bar 75 remote from the arm 76, this engagement taking place during the forward movement of the bar 75 as the machine is started into operation by the depression of the starting treadle.

In carrying out the present invention, a length size grading device is provided which operates to control the position of the templet roller 90 with relation to the templet guide 36 during the transfer of the point of operation about a shoe, to cause the trimming cutter to follow any one of a number of predetermined contour paths about the sole margin as determined by the size of the shoe being operated upon. The operation of the length size grading device is controlled by means of connections from the feed lever 60 which are manually adjustable in accordance with the length of a shoe to be operated upon, and also by means of a cam on the pattern cam shaft 58 and connections therefrom which operate to modify the movements imparted to the templet roller 90 from the feed lever 60 in accordance with a predetermined pattern during the transfer of the point of operation about the shoe.

In the preferred construction illustrated, the templet roller 90 cooperating with the templet 36, is carried on the forward end of a supporting arm 92 (see Figs. 2, 3 and 5) which is slidably mounted adjacent its forward end on a swing control lever 94, and at its rear end is connected by means of a pivot pin 96 (Fig. 13) to a U-shaped size control lever 98 for imparting in-and-out movements to the supporting arm 92 and the roller 90. The sliding connection between the arm 92 and the forward end of the swing lever 94 comprises a pin 100 which is secured to the control lever 94 and extends downwardly through a slot 102 in the roller supporting arm 92. The swing lever 94 is hung on a stationary vertical pivot 104 carried on the machine frame, and at its rear end is connected by means of a link 106 to a pivot block 108 adjustably supported in a track 110 which is formed on the feed lever 60, and passes through its pivotal axis 112. The track 110 is in the form of an arc having the link 106 as a radius, and is positioned on the feed lever 60 so that when the feed lever is in the position assumed during the transfer of the point of operation about the toe of the shoe, all portions of the track will be equidistant from the pivotal connection between the link 106 and the swing lever 94. The connections above described including the swing lever 94 and the link 106 operate to control the position of the templet roller 90 in a path parallel to the line of feed as the point of operation is transferred about the shoe. The direction and amount of this movement of the roller 90 from the normal position, which may be taken as its position as determined by that of the feed lever 60 during the operation at the toe, is determined in accordance with the length of shoe being operated upon by an adjustment of the position of the pivot block 108 in the track 110. It will readily be seen that when the pivot block 108 is located exactly over the pivot 112 of the feed lever 60, no movement is imparted to the templet roller 90, so that the contour path followed by the trimming cutter about the sole margin will correspond exactly to that of the master templet 36 which is designed for an 8C shoe. For operation upon successively larger length sizes of shoes, the pivot block 108 is moved rearwardly corresponding amounts which are gauged so that when the machine is in starting position for operation upon a shoe of the designated size, the templet roller 90 is moved a corresponding distance to the right to engage always the same point on the templet 36, as illustrated, for example, in Fig. 3, showing the machine in starting position for operation upon an 11C shoe. The movement of the feed lever 60 during the subsequent operation about the shoe, will cause the templet roller 90 to be moved gradually to the left passing through the normal position above referred to as the point of operation is transferred about the toe of the shoe. Similarly, an adjustment of the feed block forwardly from the central position over the pivot 112 for the feed lever 60 will operate to adjust the starting position of the templet roller 90 to the left for operation upon successively smaller length sizes of shoe.

The position of the pivot block 108 in the track 110 is adjusted manually through connections, see Figs. 3, 8 and 9, which comprise an adjusting slide block 114 supported in a track 116 adjacent the forward end of the feed lever 60 and connected by means of a link 118 to the pivot block 108. The adjusting slide block 114 is maintained

in any one of a number of positions corresponding to each half-length size of shoe, by the locking engagement of a spring-pressed plunger 120 in any one of a number of holes 122 in the feed lever 60. The plunger 120 is supported within a post formed on the slide block 114, and is provided at its upper end with a manual knurled control knob 124. A compression spring 126, coiled about a reduced portion of the plunger, tends normally to maintain the plunger 120 in locking engagement with one of the holes 122.

In order to cause the templet roller to follow exactly the contour path about the shoe required for each different length size of shoe, it has been found necessary also to provide means for moving the templet roller forward and back. This forward and back adjustment is controlled by means of the length size adjusting mechanism above described, as determined by the setting of the adjusting slide block 114, and by means of a cam 130, hereinafter referred to as the angular cam, on the pattern cam shaft 58 of the machine, through a sun and planet gear mechanism to be described.

Referring specifically to Figs. 12 and 13, the U-shaped lever 98 is pivotally supported by means of two pivot pins 132 within a second U-shaped lever 134 which is in turn supported by means of pivot pins 138 within a third U-shaped lever 142 carried on a stationary pivot 144. As will readily be evident from the drawings, the fulcrums for the levers 98 and 134 are only slightly out of alignment with relation to the pivotal support 96 for the rear end of the templet roller supporting arm 92, so that relatively small forward and back movements will be imparted thereto by the actuation of either of these levers. It will be noted also that the actuating connection for each of these levers 98 and 134 is located to pass through the pivotal axis 144 for the lever 142, so that either or both of the levers 98 and 134 may be adjusted to a neutral position in which they move as a unit with the lever 142 about the pivotal axis 144, and are thus rendered inoperative to vary the forward and back movements imparted to the arm 92 and templet roller 90 by the actuation of the U-shaped lever 142.

In-and-out movements are imparted to the templet roller 90 and its slide support 92 from the length size control device, through connections including a link 146 which is connected at its rear end to one of the pivot pins 138, and operates to swing the U-shaped lever 142 about its pivot. At its forward end, the link 146 is connected to a slide member 148 (see Figs. 3, 6 and 7) supported to move in a track 150 formed in a gear box member 152 which is supported on stationary pivots 154 and 156 on the machine frame and forms part of the sun and planet gear mechanism referred to. The track 150 passes through the axis of the pivots 154, 156, and follows an arcuate path having the link 146 for its radius.

The angular position of the gear box 152 is directly controlled from the feed lever 60 through the size adjusting mechanism above described including the pivot block 108 and link 106 through connections which comprise a crescent-shaped lever 158 (see Fig. 3) which is supported on a stationary pivot 160 and at one end is connected by a short link 162 to the pivotal connection between the link 106 and the rear end of the control lever 94 (Fig. 11) and at its other end is connected by a forwardly extending link 164 to the right-hand side of the gear box member 152.

The parts are so constructed and arranged that when the adjusting slide block 114 is located in position for operation upon an 8C shoe, with the pivot block 108 for the link 106 directly over the pivot 112 of the feed lever 60, the gear box 152 will be held in the position illustrated in Figs. 2 and 6, in which all portions of the track 150 are equi-distant from the pivot 138 forming the rear connection for the link 146, so that no forward or back movements will be imparted to the lever 142 and roller 90 by the movement of the slide 148 in its track.

The connections to the sun and planet gear mechanism from the angular pattern cam 130 on the pattern cam shaft 58 of the machine comprise a cam lever 168 supported on a vertically extending pivot shaft 170 and provided with a roller 172 arranged for engagement against the cam 130. The cam lever 168 is connected by means of a link 174 to a lever arm 176 carried on a rock shaft 178 which also has supported thereon a lever arm 180 connected by a forwardly extending link 182 to a gear segment lever 184 supported on the pivot 156 for the gear box 152. The movements imparted to the gear segment lever 184 from the angular cam 130 and the turning movements imparted to the casing 152 from the feed lever 60, together control the operation of the sun and planet mechanism hereinafter described to impart predetermined movements to the slide 148 along the track 150. These movements of the slide 148 in combination with the angular movements of the gear box 152 and track 150 supported thereon, operate to determine the direction and amount of the forward and back movements imparted to the templet roller 90.

The sun and planet mechanism through which movements are imparted to the slide 148 comprises a vertically extending shaft 186 rotatably supported in the gear box 152 having secured thereto a gear 188 and to the bottom end thereof a pinion 190 which engages with a rack 192 rigidly secured to the machine frame and formed in the shape of an arc with the pivot 154, 156 of the gear box 152 as a center. Loosely mounted on the shaft 186 above the gear 188 is a large gear 194 which meshes with a gear segment 196 formed on the gear segment lever 184. Mounted on the under side of the large gear 194 are three planet gears 198 which are arranged to mesh with the gear 188 above referred to, and also with an internal gear 200 formed on a member 202 which is loosely mounted to turn on the shaft 186, and is provided with a gear segment 204 which meshes with a rack 206 on the slide member 148.

With this construction and arrangement of the sun and planet mechanism, rotational movements may be imparted to the member 202 to move the slide member 148 in the track 150 by turning the gear box 152 on its pivot 154, 156 which operates by the engagement of the pinion 190 with the stationary rack 192 to rotate the gear 188 and planet gears 198 meshing therewith, which in turn operate through their engagement with the internal gear 200 to rotate the member 202. Movement is imparted to the rack 148 also from the angular cam 130 which operates through the gear segment lever 184 and segment 196 to rotate the large gear 194, thus causing the planet gears to be moved bodily around the gear 188, and thereby through the engagement of the planet gears with the internal gear 200 rotating the member 202 to move the slide 148 in one direction or the other on its track 150. 75

Thus, the rocking of the gear box 152 around its pivot 154, 156, under the influence of the connections including the crescent-shaped lever 158 and link 106 from the feed lever 60, operates to swing the track 150 away from its position normal to the pivotal connection 138 for the link 146, and at the same time through the operation of the sun and planet mechanism above described, serves to impart lengthwise movement to the slide 148 in the track 150, and thereby to rock the lever 142 about its pivot to move the templet roller 90 in or out, as the case may be. This movement of the slide 148 is modified as above described by the operation of the angular cam 130 and its connections including the gear segment lever 184 forming part of the sun and planet gear mechanism.

The principle of operation of connections from the feed lever 60 and angular cam 130 including the sun and planet mechanism above described to effect the desired in-and-out adjustments in accordance with the length size of shoe being operated upon during the transfer of the point of operation about the shoe, will be readily understood in connection with the explanatory diagram Fig. 19 of the drawings. As shown in this figure, all the adjustments are made from a single reference point 210 at the toe of the shoe, which is always located at the same point with relation to the master templet regardless of variations in length or width of shoe being operated upon. In the diagram referred to, the line 212 represents the contour path followed by the trimming cutter around the sole margin of a size 8C shoe. The line 214 represents the outline of the master templet, which is designed to correspond exactly to the margin contour of a size 8C shoe, so that the templet roller 90, when maintained in a stationary position, will operate by engagement with the templet during the transfer of the point of operation about the shoe, to cause the trimming cutter to follow exactly the desired contour path required for the trimming of an 8C shoe. The dotted outline 216 represents the margin contour of a size 11C shoe in the position which it will occupy with relation to the templet contour 214 when supported on the jack. Similarly, the dotted line 218 represents the margin contour of a 5C shoe when supported in operating position on the jack. The circles 220 on the templet contour 214 represent a series of points of contact of the templet roller 90 against the templet during the transfer of the point of operation about an 8C shoe. The circles 222 on the contour line 212 of an 8C shoe, represent corresponding positions of the trimming cutter 28 against the shoe, as shown by construction lines 224 connecting corresponding circles on the contour lines 212 and 214. In order to ascertain the proper relative position of the trimming cutter 28 and the templet roller 90 for each of the stations illustrated by the circle 220 during the operation about a relatively larger or smaller shoe, a number of construction lines 226 have been drawn radiating from the reference point 210, and passing through each of the circles 222. The point of intersection of each construction line 226 with the contour path 216 for an 11C shoe, is marked by a circle 228, and similarly, the point of intersection of each construction line 226 with the margin contour line 218 for a 5C shoe, is marked by a circle 230.

It will readily be seen from an inspection of Fig. 19, that the relative position of the trimming cutter 28 and the templet roller 90 for each of

the stations or points of contact 220 of the templet roller 90 with the contour outline 214 of the templet 36 may be determined for each length size of shoe being operated upon by the position of the trimming cutter on the corresponding construction line 226. Applicant's length size grading device above described is arranged to impart forward and back movements and lengthwise movements in the line of feed to the roller 90 which are arranged to cause the roller for each of the operating stations above described to be located on a line which is parallel to the corresponding construction line 226, and passing through the circle 220, and thus to secure the proper relative positions of the cutter and roller 15 illustrated by the diagram. The length and direction of movement of the roller 90 along this imaginary path from the normal position indicated by the corresponding circle 220 is determined for each operating station directly by 20 the position of the feed lever 60 and link 106 in accordance with the setting of the pivot block 108 for the length of shoe being operated upon. At the starting position for operation upon a shoe, the roller 90 will be located at the maximum 25 distance away from the normal position indicated by the circle 220, and gradually approaches the normal position indicated by each successive circle 220 due to the continued movement of the feed lever 60 until the toe is reached when the 30 roller 90 is brought exactly to its normal position, as indicated by the corresponding circle or reference point 210. During the subsequent operation on the opposite side of the shoe, the roller is again moved away from its normal position by 35 an amount which is proportional to the movement of the feed lever, increasing gradually to a maximum at the end of an operation on the opposite side of the shank portion of the shoe. It is the function of the sun and planet mechanism controlled by the angular cam 130 and by the connections from the feed lever 60 to adjust the forward and back position of the roller 90 as the point of operation is transferred about the shoe to cause the roller 90 at all times to travel 40 along this imaginary path parallel to the construction line 226 corresponding to each successive station 220 in the transfer of the point of operation about the shoe.

The relative starting positions of the templet 36 roller 90 and the cutter 28 for operation upon an 11C shoe are shown in Figs. 3 and 18. The adjusting slide block 114 and pivot block 108 have been adjusted to their extreme rear position, so that a maximum throw is imparted to the roller 50 90 by any movement of the feed lever 60. As the shoe supported on the jack is now brought into operating position, it will be seen that the feed lever 60 is moved to its extreme position to the right, thus causing the roller 90 also to be moved 55 to the right a proportional amount. This movement of the feed lever 60 at the same time acts through the link 106, crescent-shaped lever 158 and link 164 to swing the gear box 152 and track 150 about the pivot 154, 156. The movement of 60 the gear box in turn is rendered operative through the operation of the sun and planet mechanism above described, as modified by the starting position of the angular cam 130, to move the slide 148, retracting the roller 90 a slight 65 amount so that the roller is maintained on a line passing through the starting station 220 and parallel to the construction line 226. As the point of operation progresses toward the toe of 70 the shoe, the movement of the feed lever causes 75

the roller 90 to be gradually moved to the left until at the toe it is directly in line with the cutter 28. The continued movement of the feed lever to the left as the point of operation is transferred along the other side of the shoe, causes the feed roller 90 also to continue its movement to the left by an amount which is proportionally increased as the point of operation again approaches the shank portion of the shoe. The in-and-out movements of the roller 90 are controlled by the movement of the feed lever 60 and by the rotation of the angular cam 130 acting through the sun and planet mechanism as above set forth, to cause the resulting movement of the roller 90 from the normal position for each successive station represented by the circles 220, to take place along a line parallel to the corresponding construction line 226, so that the relative positions of the roller 90 and cutter 28 at each of the operating stations about the shoe will be accurately represented by the relative positions of the circles 220 and 228. The actual path of movement of roller 90 about an 11C shoe is indicated by a dot-and-dash line 232 in Fig. 18.

25 The relative starting position of the templet roller 90 and the cutter 28 for operation upon an 8C shoe is shown in Figs. 2 and 17. The adjusting slide block 114 has been moved to its middle or size 8 position, in which the pivot block 108 is directly over the pivot 112 of the feed lever 60, so that no movement is imparted to the templet roller 90 by the swinging movements of the feed lever 60 during the transfer of the operation about the shoe. The corresponding circles 220 and 222 connected by construction lines 224 (see Fig. 19) illustrate the relative positions of the templet roller 90 and cutter 28 for each successive operating station during the operation on an 8C shoe.

40 The relative starting position of the templet roller 90 and the cutter 28 for operation upon a 5C shoe is shown in Fig. 16, in which the adjusting slide block 114 and pivot block 108 have been adjusted to their extreme forward position on the feed lever 60, so that as the shoe supported on the jack is brought to starting position and the feed lever 60 is moved to the right, the swing lever 94 is moved in a clockwise direction from the position shown in Fig. 2, causing the templet roller 90 to be moved a proportional distance to the left. This movement of the feed lever 60 at the same time acts through the link 106, crescent-shaped lever 158 and link 164 to swing the gear box 152 and track 150 in a counterclockwise direction about its pivot 154, 156. The movement of the gear box in turn is rendered operative through the operation of the sun and planet mechanism above described, as modified by the starting position of the angular cam 130, to move the slide 148, advancing the roller 90 a slight amount. This relative starting position is illustrated in diagrammatic form in Fig. 19, by the relative positions of the circle 230 representing the starting position of the cutter, and the corresponding circle 220 representing the starting position of the templet roller 90. As the point of operation progresses toward the toe of the shoe, the movement of the feed lever to the left causes the roller 90 to be gradually moved to the right until at the toe it is directly in line with the cutter 28. Continued movement of the feed lever to the left, as the point of operation is transferred along the other side of the shoe, causes the feed roller 90 always to continue its

movement to the right by an amount which is proportionally increased as the point of operation again approaches the shank portion of the shoe. The in-and-out movements of the roller 90 are controlled by the movement of the feed lever 60 and by the rotation of the angular cam 130 acting through the sun and planet mechanism as above set forth, to cause the resulting movement of the roller 90 from the normal position for each successive station represented by the circles 220 to take place along a line parallel with the corresponding construction line 226, so that the relative positions of the roller 90 and cutter 28 at each of the operating stations about the shoe will be accurately represented by the relative positions of the circles 220 and 230. The actual path of movement of the roller 90 about a 5C shoe is indicated by a dot-and-dash line 234 in Fig. 16.

20 There is also provided in the present construction a width size grading mechanism which operates in combination with the length size grading mechanism above described to cause the trimming cutter 28 to follow any one of a number of predetermined contour paths which extend over the entire range of widths of shoe for each length, as determined by the setting of the length size adjusting slide block 114. The width size control mechanism comprises mechanism for imparting additional in-and-out movements to the templet roller 90 which are additive to those imparted by the size grading mechanism. The width size grading mechanism comprises a width cam 240 (see Fig. 3) on the pattern shaft 58, which is engaged by a cam lever 242 on the pivot shaft 170.

25 The forwardly extending arm of the cam lever 242 is connected by a link 244 to a lever arm 246 secured to a vertically extending shaft 248 pivoted on the machine frame and provided at its upper end with an arcuate track 250 which extends through the pivotal axis of the shaft 248. An adjustable slide block 252 (see Figs. 14 and 15) supported in the track 250 is connected by a link 254 to one arm of a lever 256 supported on a vertical pivot 258, and connected at its other end to a rearwardly extending link 260. At its rear end, the link 260 is connected to the U-shaped lever 134 at a point which passes through the axis of rotation of the length size adjusting lever 142. With this construction and arrangement of the width control mechanism, it will readily be seen that when the slide block 252 is located exactly on the pivotal axis of the lever 246, no movement is imparted to the connections including the lever 256, link 260 and width size control lever 134. For this adjustment of the parts, the pivotal connection between the link 260 and the lever 134 is located in axial alignment with the pivot 144 of the lever 142, so that the lever 134 swings as a unit with the length size control lever 142. When the pivot block 252 is adjusted to the right from the position shown in Fig. 3, movement is imparted to the connections above described including the width size control lever 134 to move the templet roller 90 forwardly a proportional amount determined by the setting of the block 252 for the narrower size shoes. Similarly, an adjustment of the width size control pivot block 252 to the left, from the position shown in Fig. 3, will operate to adjust the width mechanism for operation upon wider shoes of any given length size, as determined by the setting of the length size adjusting slide block 114.

As best shown in the detail views Figs. 14 and 15, the slide block 252 has mounted therein a vertically extending plunger 264 which is provided at its upper end with a knurled control knob 266, and is arranged for locking engagement with any one of a series of recesses 268 formed in the bottom of the track 250. A compression spring 270 coiled about the plunger 264 between a collar 272 and a shoulder 274 formed in the block 252, tends to force the plunger 264 downwardly into locking position.

In accordance with one feature of the invention, an adjustment is provided in the mechanism for controlling the position of the templet roller 90 to determine the width of the margin about the shoe sole left by the edge trimming operation independently of the length, width or style of shoe being operated upon. In order to provide for such an adjustment, the link 260 forming a part of the width grading mechanism, is adjustably connected to the lever 256 by means of a nut 276 which is mounted on a threaded portion of the link 260, and is pivotally supported by pins 277 in the forked end of the lever 256, so that rotational movement of the link 260 will operate either to lengthen or shorten the link connection between the lever 256 and the U-shaped lever 134. In order to permit the free rotation of the link, the rear end thereof is screw-threaded into a nut 278 which forms the pivotal connection with the lever 134. A manual control knob 279 secured to the forward end of the link 260 provides convenient means for adjustment of the angular position of the link 260. It will readily be seen from an inspection of Figs. 3 and 12 of the drawings, that the adjustment thus provided serves to control the angular position of the U-shaped width control lever 134, and thus serves to provide an in-and-out adjustment in the position of the slide bar 92 and templet roller 90 which is independent of the operation of the length and width size grading devices above described.

Further in accordance with the present invention, the machine herein disclosed is provided with means for varying the contour path followed by the trimming cutter in order to provide for variations in the style of shoe operated upon without the necessity of employing a different master templet. To this end a character cam 280 is supported on a supplemental shaft 282 which is driven in synchronism with the pattern shaft 58 through connections which include a pinion 284 secured to turn with the character cam 280 on shaft 282 (see Figs. 1 and 2) and a pinion 286 supported on the vertical shaft 287 from which the pattern cam shaft 58 is driven by the engagement of one of the gears 288 thereon with the usual pattern driving gear 290 secured to the pattern shaft 58.

The connections from the character cam 280 for imparting in-and-out movements to the templet roller 90 (see Figs. 3, 12 and 13) comprise a cam lever 292 supported on a fixed pivot 294, and provided at one end with a roller 296 arranged for engagement with the character cam 280. The cam lever 292 is connected at its other end by means of a rearwardly extending link 298 to the U-shaped lever 98. The character cam 280 is illustrated in the drawings in the form of a disk which operates to maintain the pivotal connection between the link 298 and U-shaped lever 98 at all times in axial alignment with the pivot 144, so that no movement is imparted to the templet roller 90 by the character cam 280. It will readily be seen, however, that desired modi-

fications in the characteristic outline or style of the shoe as determined by the shape of the master templet 36, may be obtained by varying the shape of the character cam disk 280 so that increments of movement are imparted to the templet roller 90 by movement of the U-shaped lever 98 which serve to vary the characteristic movements imparted to the roller 90 by the length and width size grading mechanisms above described.

It will readily be understood that the machine herein disclosed embodying applicants' size grading device, may be readily adapted with minor adjustments for operation upon shoes over a range of sizes other than that specifically described, and on a relatively larger number of different styles of shoe. In order to secure a different range in the size of shoes operated upon, it is necessary only to utilize a different master templet which will extend the range of adjustment to either larger or smaller size shoes as may be desired. For operation upon widely different styles of shoes, a different set of pattern cams may be necessary to impart the correct tipping and turning movements to the shoe during the transfer of the point of operation about the shoe margin. The pattern cam shaft 58 of applicants' machine is constructed and arranged to have mounted thereon a number of sets of pattern cams which are vertically adjustable to permit the substitution of one set for another in operating relationship to the follower connections for actuating the jack. Inasmuch as the mechanism for achieving this adjustment is well-known in the art, and is fully illustrated and described in the patent to Alfred R. Morrill No. 1,952,770 dated March 27, 1934, no description thereof is believed necessary.

The nature and objects of the invention having been indicated, and a machine embodying the several features of the invention having been specifically described, what is claimed is:

1. A machine for operating upon the bottom margin of a shoe having, in combination, means for operating upon a shoe, a shoe supporting jack, means for relatively moving the jack and operating means to transfer the point of operation about the shoe, a templet, a movable guiding device engaging the templet to relatively position the jack and operating means to locate the shoe laterally with relation to the line of feed at the point of operation, means for positioning the guiding device relatively to the operating means during the transfer of the point of operation about the shoe to cause the operating means to follow any one of a plurality of predetermined length size contour paths about the shoe, said positioning means having provision for adjustment to vary the path followed by the operating means with relation to said templet in accordance with the length size of shoe being operated upon.

2. A machine for operating upon the bottom margin of a shoe having, in combination, means for operating upon a shoe, a shoe supporting jack, a templet supported thereon having a guiding contour surface determined for a shoe of a predetermined length size, means for locating a shoe on the jack in a predetermined position with relation to the templet, a movable guiding device engaging the templet to relatively position the jack and operating means to locate the shoe laterally with relation to the line of feed at the point of operation, and means for positioning the guiding device during the transfer of the point of operation about the shoe to cause the

- operating means and guiding device to engage at all times with proportionate points respectively of the shoe margin and of the templet, said positioning means having provision for adjustment to vary the path followed by the operating means with relation to said templet in accordance with the length size of shoe being operated upon.
3. A machine for operating upon the bottom margin of a shoe having, in combination, means for operating upon a shoe, a shoe supporting jack, a templet supported thereon having a guiding contour surface determined for a shoe of a predetermined length size, means for locating shoes of varying length sizes on the jack in predetermined relation to the templet, a movable guiding device engaging the templet to relatively position the jack and operating means to locate the shoe laterally with relation to the line of feed at the point of operation, and means including a connection movable with the shoe for positioning the guiding device relatively to the operating means during the transfer of the point of operation about the shoe to cause the operating means and the guiding device to engage at all times with proportionate points respectively of the contour outline to be followed by the operating means about the jacked shoe and of the templet.
4. A machine for operating upon the bottom margin of a shoe having, in combination, means for operating upon a shoe, a shoe supporting jack, a templet supported thereon having a guiding contour surface determined for a shoe of a predetermined length size, means for locating a shoe on the jack with the toe portion thereof in a predetermined position with relation to the templet, a movable guiding device engaging the templet to relatively position the jack and operating means to locate the shoe laterally with relation to the line of feed at the point of operation, and means including a connection movable with the shoe for positioning the guiding device relatively to the operating means in the line of feed during the transfer of the point of operation about the shoe to cause the operating means and guiding device to engage at all times with proportionate points respectively of the shoe margin and of the templet, said positioning means having provision for adjustment in accordance with the length size of shoe being operated upon.
5. A machine for operating upon the bottom margin of a shoe having, in combination, means for operating upon a shoe, a shoe supporting jack, a templet supported thereon having a guiding contour surface determined for a shoe of a predetermined length size, means for locating a shoe on the jack with the toe portion thereof in a predetermined position with relation to the templet, a movable guiding device engaging the templet to relatively position the jack and operating means to locate the shoe laterally with relation to the line of feed at the point of operation, means for positioning the guiding device relatively to the operating means in the line of feed and transversely thereof during the transfer of the point of operation about the shoe to cause the operating means and guiding device to engage at all times with proportionate points respectively of the shoe margin and templet, and means for adjusting said means for positioning the guiding device to vary the path followed by the operating means with relation to said templet in accordance with the length size of shoe being operated upon.
6. A machine for operating upon the bottom margin of a shoe having, in combination, means for operating upon a shoe, a shoe supporting jack, a templet supported thereon having a guiding contour surface determined for a shoe of a predetermined length size, means for locating shoes of varying length sizes on the jack in predetermined relation to the templet, a movable guiding device engaging the templet to relatively position the jack and operating means to locate the shoe laterally with relation to the line of feed at the point of operation, a member movable with the shoe and connections therefrom for positioning the guiding device relatively to the operating means in the line of feed during the transfer of the point of operation about the shoe to cause the operating means and guiding device to engage at all times with proportionate points respectively of the shoe margin and of the templet, and connections from said member movable in accordance with a predetermined pattern during the transfer of the point of operation about the shoe for positioning the guiding device laterally of the line of feed.
7. A machine for operating upon the bottom margin of a shoe having, in combination, means for operating upon a shoe, a shoe supporting jack, means for moving the jack relatively to the operating means to transfer the point of operation about the shoe, a templet supported on the jack having a guiding contour surface determined for a shoe of a predetermined length size, means for locating shoes of varying length sizes on the jack in predetermined relation to the templet, a movable guiding device engaging the templet to relatively position the jack and operating means to locate the shoe laterally with relation to the line of feed at the point of operation, a member movable with the shoe and connections therefrom for positioning the guiding device relatively to the operating means in the line of feed during the transfer of the operation about the shoe to cause the operating means and guiding device to engage at all times with proportionate points respectively of the shoe margin and of the templet, connections from said member movable in accordance with a predetermined pattern during the transfer of the point of operation about the shoe for positioning the guiding device laterally of the line of feed, and means for adjusting said connections in accordance with the length size of shoe being operated upon to cause the operating means to follow the contour outline of the jacked shoe.
8. A machine for operating upon the bottom margin of a shoe having, in combination, means for operating upon a shoe, a shoe supporting jack, means including a feed member for moving the jack relatively to the operating means to transfer the point of operation about the shoe, a templet supported thereon having a guiding contour surface determined for a shoe of a predetermined length size, means for locating a shoe on the jack with the toe portion thereof in a predetermined position with relation to the templet, a movable guiding device engaging the templet to relatively position the jack and operating means to locate the shoe laterally with relation to the line of feed at the point of operation, and a length size grading device comprising a connection from said feed member for positioning the guiding device relatively to the operating means in the line of feed during the

transfer of the operation about the shoe to cause the operating means and guiding device to engage at all times with proportionate points respectively of the shoe margin and the templet, a cam actuated in timed relation to the transfer of the operation around the shoe, and connections acted upon jointly by said feed member and by said cam to position the guiding device transversely of the line of feed to cause the operating means to follow a predetermined length size contour path about the jacked shoe.

9. A machine for operating upon the bottom margin of a shoe having, in combination, means for operating upon a shoe, a shoe supporting jack, means including a feed lever for moving the jack relatively to the operating means to transfer the point of operation about the shoe, a templet supported thereon having a guiding contour surface determined for a shoe of a predetermined length size, means for mounting a shoe on the jack with the toe portion thereof in a predetermined position with relation to the templet, a movable guiding device engaging the templet to relatively position the jack and operating means to locate the shoe laterally with relation to the line of feed at the point of operation, and a length size grading device comprising a connection from said feed lever having provision for adjustment in accordance with the length size 30 of the jacked shoe and operative during the transfer of the operation about the shoe to cause the guiding device and operating means to engage at all times with proportionate points respectively of the templet and the contour outline of the shoe margin, a cam rotatable in timed relation to the transfer of the operation about the shoe, and means acted upon jointly by said adjustable connection and by said cam for positioning the guiding device transversely of the line of feed during the transfer of the operation about the shoe.

10. A machine for operating upon the bottom margin of a shoe having, in combination, means for operating upon a shoe, a shoe supporting jack, means including a feed lever connected to the toe portion of the jack for moving the jack relatively to the operating means to transfer the point of operation about the shoe, a templet having a fixed contour and supported in a predetermined relationship to the jack and shoe supported thereon, a movable guiding device engaging the templet to relatively position the jack and operating means to locate the shoe margin laterally with relation to the line of feed at the point of operation, and means for controlling the movements of the guiding device during the transfer of the operation about the shoe to cause the operating means to follow any one of a plurality of predetermined marginal contour paths about the shoe comprising a connection from the feed lever for moving the guiding device in the line of feed with relation to the operating means an amount which is proportioned to the distance of the point of operation from a reference point located at the toe of the shoe, means for adjusting the ratio of said proportional movements in accordance with the length size of shoe being operated upon, means actuated by said connections for moving the guiding device transversely of the line of feed, a cam, and connections actuated thereby for modifying the operation of said latter means to move the guiding device transversely of the line of feed in accordance with a predetermined pattern during the transfer of the operation about the shoe.

11. A machine for operating upon the bottom margin of a shoe having, in combination, means for operating upon a shoe, a shoe supporting jack, a templet supported thereon having a guiding contour surface determined for a shoe of a predetermined length and width size, means for locating a shoe on the jack in a predetermined position with relation to the templet, a movable guiding device engaging the templet to relatively position the jack and operating means to locate the shoe laterally with relation to the line of feed at the point of operation, and means for positioning the guiding device relatively to the operating means during the transfer of the operation about the shoe to cause the operating means to follow any one of a plurality of predetermined length and width size contour paths about a shoe supported on the jack, said positioning means having provision for adjustment in accordance with both the length size and width size of the shoe being operated upon.

12. A machine for operating upon the bottom margin of a shoe having, in combination, means for operating upon a shoe, a shoe supporting jack, means for relatively moving the jack and operating means to transfer the point of operation about the shoe, a templet supported in a predetermined relationship to the jack and shoe supported thereon, a movable guiding device engaging the templet to relatively position the jack and operating means to locate the shoe laterally with relation to the line of feed at the point of operation, means for positioning the guiding device relatively to the operating means during the transfer of the operation about the shoe to cause the operating means to follow a predetermined length size contour path corresponding to the length size of the jacked shoe, and means for modifying the position of the guiding means during the transfer of the operation about the shoe to cause the operating means to follow a predetermined width size contour outline corresponding to that of the jacked shoe.

13. A machine for operating upon the bottom margin of a shoe having, in combination, means for operating upon a shoe, a shoe supporting jack, means for relatively moving the jack and operating means to transfer the point of operation about the shoe, a templet supported in a predetermined relationship to the jack and shoe supported thereon, a movable guiding device engaging the templet to relatively position the jack and operating means to locate the shoe laterally with relation to the line of feed at the point of operation, a length size grading means for positioning the guiding device relatively to the operating means during the transfer of the point of operation about the shoe to cause the operating means to follow any one of a plurality of predetermined contour paths about the shoe, said length size grading means having provision for adjustment in accordance with the length size of shoe being operated upon, and width size grading means for positioning the guiding device during the transfer of the operation about the shoe, said width size grading means having provision for adjustment to cause the operating means to follow any one of a plurality of predetermined contour paths corresponding to different widths of shoe of the length size determined by the adjustment of the length size grading means.

14. A machine for operating upon the bottom margin of a shoe having, in combination, means for operating upon a shoe, a shoe supporting jack, a templet supported thereon having a guid-

ing contour surface determined for a shoe of a predetermined length and width size, means for locating shoes of varying length and width sizes on the jack in predetermined relation to the templet, a movable guiding device engaging the templet to relatively position the jack and operating means to locate the shoe laterally with relation to the line of feed at the point of operation, length size grading means having provision

- 5 for adjustment in accordance with the length size of the jacked shoe for positioning the guiding device relatively to the operating means during the transfer of the point of operation about the shoe to cause the operating means and guiding device to engage at all times with proportionate points respectively of the shoe margin and of the templet, and width size grading means having provision for adjustment in accordance with the width size of the jacked shoe for positioning the guiding device relatively to the operating means to cause the operating means to follow a predetermined contour path about the jacked shoe.

15. A machine for operating upon the bottom margin of a shoe having, in combination, means for operating upon a shoe, a shoe supporting jack, a templet supported thereon having a guiding contour surface determined for a shoe of a predetermined length and width size, means for mounting shoes of varying length and width size on the jack in predetermined relation to the templet, a movable guiding device engaging the templet to relatively position the jack and operating means to locate the shoe laterally with relation to the line of feed at the point of operation, length size grading means having provision for adjustment in accordance with the length size of the jacked shoe for positioning the guiding device relatively to the operating means in the line of feed and transversely thereof during the transfer of the point of operation about the shoe to cause the operating means and guiding device to engage at all times with proportionate points respectively of the shoe margin and templet, and width size grading means having provision for adjustment in accordance with the width size of the jacked shoe and constructed and arranged to modify the position of the guiding device laterally of the line of feed during the transfer of the operation about the shoe to cause the operating means to follow a predetermined contour path corresponding to the width size of the jacked shoe.

16. A machine for operating upon the bottom margin of a shoe having, in combination, means for operating upon a shoe, a shoe supporting jack, a templet supported thereon having a guiding contour surface determined for a shoe of a predetermined length and width size, means for mounting shoes of varying length and width sizes on the jack in predetermined relation to the templet, a movable guiding device engaging the templet to relatively position the jack and operating means to locate the shoe laterally with relation to the line of feed at the point of operation, length size grading means comprising a member movable with the shoe and connections therefrom for positioning the guiding device relatively to the operating means in the line of feed during the transfer of the operation about the shoe to cause the operating means and guiding device to engage at all times with proportionate points respectively of the shoe margin and of the templet, connections from said member movable in accordance with a predetermined pattern during the transfer

of the operation about the shoe for positioning the guiding device laterally of the line of feed, and width grading means having provision for adjustment in accordance with the width size of the jacked shoe acting on said connections for transversely positioning the guiding device to cause the operating means to follow the marginal contour outline of the jacked shoe.

17. In a machine for operating upon the bottom margin of a shoe having means for operating upon a shoe, a shoe supporting jack and means including a feed lever connected to the toe portion of the jack for moving the jack to transfer the point of operation about the shoe, the combination of a templet supported to have a fixed spaced relation to the toe of a jacked shoe, a movable templet guide member engaging the templet to relatively position the jack and operating means to locate the shoe laterally with relation to the line of feed at the point of operation, and length size grading means for controlling the position of said guiding device transversely and in the direction of the line of feed comprising a swing lever supporting the guide member to move in the direction of the line of feed, a link between said feed lever and swing lever, and a pivotal connection between the link and feed lever adjustable on the feed lever in an arcuate path passing through the pivotal axis of the feed lever, said arcuate path having the length of the link as a radius and located normally thereto for a position of the feed lever with the point of operation at the toe of the shoe, and means controlled from said link for imparting positioning movements to the templet guide member transversely of the line of feed.

18. In a machine for operating upon the bottom margin of a shoe having means for operating upon a shoe, a shoe supporting jack and means including a feed lever connected to the toe portion of the jack for moving the jack to transfer the point of operation about the shoe, the combination of a templet supported to have a fixed spaced relation to the toe of a jacked shoe, a movable templet guide member engaging the templet to relatively position the jack and operating means to locate the shoe laterally with relation to the line of feed at the point of operation, and length size grading means for controlling the position of said guiding device transversely and in the direction of the line of feed comprising a slide support for the guide member movable transversely of the line of feed, a swing lever support for the templet guide member movable in the direction of the line of feed, a link between said feed lever and swing lever, a pivotal connection between the link and feed lever adjustable for length size of shoe on the feed lever in an arcuate path passing through the pivotal axis of the feed lever, said arcuate path having the length of the link as a radius and located normally thereto for a position of the feed lever with the point of operation at the toe of the shoe, a connection actuated by said link for imparting positioning movements to said slide support transversely of the line of feed, a cam and connections actuated thereby for modifying the positioning movements imparted by said connection in accordance with a predetermined pattern during the transfer of the operation about the shoe.

19. In a machine for operating upon the bottom margin of a shoe having means for operating upon a shoe, a shoe supporting jack and means including a feed lever connected to the toe portion of the jack for moving the jack to transfer

the point of operation about the shoe, the combination of a templet supported to have a fixed spaced relation to the toe of a jacked shoe, a movable templet guide member engaging the templet to relatively position the jack and operating means to locate the shoe laterally with relation to the line of feed at the point of operation, and length size grading means for controlling the position of said guiding device transversely and in the direction of the line of feed comprising a slide support for the templet guide member movable transversely of the line of feed, a swing lever support for the templet guide member movable in the direction of the line of feed, a connection from the feed lever adjustable in accordance with the length size of shoe being operated upon for actuating said swing lever to cause the templet guide member to engage always with a point on the templet corresponding to the point of engagement of the operating means with the shoe margin, connections for imparting transverse positioning movements to said slide support comprising a link connected to actuate said slide, an actuating lever, a pivotal connection between said lever and link movable in an arcuate path passing through the pivotal axis of the lever and having the length of the link as a radius, means actuated by said adjustable connection from the feed lever for rotating said lever, a pattern cam and a differential mechanism controlled by rotational movements of said lever and by said cam for moving said pivotal connection along its path in accordance with a predetermined pattern during the transfer of the operation about the shoe.

20. In a machine for operating upon the bottom margin of a shoe having means for operating upon a shoe, a shoe supporting jack and means including a feed lever connected to the toe portion of the jack for moving the jack to transfer the point of operation about the shoe, the combination of a templet supported to have a fixed spaced relation to the toe of a jacked shoe, a movable templet guide member engaging the templet to relatively position the jack and operating means to locate the shoe laterally with relation to the line of feed at the point of operation, and length size grading means for controlling the position of said guiding device transversely and in the direction of the line of feed comprising a slide support for the templet guide member movable transversely of the line of feed, a swing lever support for the templet guide member movable in the direction of the line of feed, a link between said feed lever and swing lever, a pivotal connection between the link and feed lever adjustable on the feed lever in an arcuate path passing through the pivotal axis of the lever, said arcuate path having the length of the link as a radius and located normally thereto for a position of the feed lever with the point of operation at the toe of the shoe, connections from said link for imparting transverse positioning movements to said slide support including a lever directly connected to be actuated by said link, a link between said lever and slide member having a pivotal connection with said lever movable on the lever in an arcuate path passing through the pivotal axis of the lever, said arcuate path having the length of said latter link as a radius and located normally thereto for a position of the feed lever and intervening connections with the point of operation at the toe of the shoe, a cam rotatable in timed relation to the transfer of the point of operation about the shoe, differential gearing and connections thereto from said lever and from said cam for moving said latter pivotal connection on the lever in accordance with a predetermined pattern during the transfer of the operation about the shoe.

nections from said link for imparting transverse positioning movements to said slide support including a lever directly connected to be actuated by said link, a link between said lever and slide member having a pivotal connection with said lever movable thereon in an arcuate path passing through the pivotal axis of the lever, and having the length of said latter link as a radius, a cam, and differential gearing controlled jointly by said lever and by said cam for imparting positioning movements to said latter pivotal connection in accordance with a predetermined pattern during the transfer of the operation about the shoe.

21. In a machine for operating upon the bottom margin of a shoe having means for operating upon a shoe, a shoe supporting jack and means including a feed lever connected to the toe portion of the jack for moving the jack to transfer the point of operation about the shoe, the combination of a templet supported to have a fixed spaced relation to the toe of a jacked shoe, a movable templet guide member engaging the templet to relatively position the jack and operating means to locate the shoe laterally with relation to the line of feed at the point of operation, and length size grading means for controlling the position of said guiding device transversely and in the direction of the line of feed comprising a slide support for the templet guide member movable transversely of the line of feed, a swing lever support for the templet guide member movable in the direction of the line of feed, a link between said feed lever and swing lever, a pivotal connection between the link and feed lever adjustable on the feed lever in an arcuate path passing through the pivotal axis of the feed lever, said arcuate path having the length of the link as a radius and located normally thereto for a position of the feed lever with the point of operation at the toe of the shoe, connections from said link for imparting transverse positioning movements to said slide support including a lever directly connected to be actuated by said link, a link between said lever and slide member having a pivotal connection with said lever movable on the lever in an arcuate path passing through the pivotal axis of the lever, said arcuate path having the length of said latter link as a radius and located normally thereto for a position of the feed lever and intervening connections with the point of operation at the toe of the shoe, a cam rotatable in timed relation to the transfer of the point of operation about the shoe, differential gearing and connections thereto from said lever and from said cam for moving said latter pivotal connection on the lever in accordance with a predetermined pattern during the transfer of the operation about the shoe.
